RESILIENT SUPPORT

James Piliero, Astoria, N. Y., assignor to Dickson
Wire & Cable Corp., Long Island City, N. Y., a
corporation of New York

Application February 10, 1941, Serial No. 378,181

11 Claims. (Cl. 5—247)

This invention relates to resilient supports and more particularly to the type of resilient supports known generally as spring bottoms.

Spring bottoms made in accordance with the invention are particularly well adapted for bed springs; for furniture, such as chairs, divans and the like, for vehicle seats, and other upholstered parts such as automobile back rests and interiors, and for other similar uses where a resilient support is desired to form a base upon which to support stuffed or upholstered coverings.

Among the characteristics desired in resilient supports of the type to which this invention relates are that the support or bottom (herein referred to generally as "spring bottom") bear the load placed upon it without undue or permanent sagging; that it have sufficient flexibility to conform to the shape of the body and distribute the load sufficiently to prevent undue strains upon any particular or single member; that it have sufficient resiliency to provide a comfortable support for the person when in use; that it yield when stressed and return to its original position when the stress is relieved without squeaking, scraping or clicking, and that it may be manufactured and assembled with the article with which it may be used economically and with facility.

The invention lends itself admirably to the accomplishment of the foregoing objectives as well as others mentioned hereinafter.

According to one form of the invention, an upper and lower frame is provided. The lower frame provides support for a plurality of elliptical springs which are connected to a plurality of strips. The strips are connected to the upper frame and provide a resilient supporting surface. The supporting surface strips may be interconnected in various combinations with the upper frame and with each other and means are provided to prevent undesirable longitudinal and lateral play or movement of the upper frame and supporting surface relative to the lower frame.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken

in connection with the accompanying drawings forming a part herein, in which

Fig. 1 is a top plan view of a spring bottom constructed in accordance with the invention, the particular structure being a bed spring for supporting a mattress or the like;

Fig. 2 is a side view in elevation of the structure of Fig. 1;

Fig. 3 is a partial top plan view of the structure shown in Fig. 1 but to larger scale with parts broken away;

Fig. 4 is a view on line 4—4 of Fig. 3;

Fig. 5 is a view on line 5—5 of Fig. 3;

Fig. 6 is a view on line 6—6 of Fig. 3;

Fig. 7 is a partial view in elevation and cross section of a modified form of structure showing a supporting surface of different configuration as distinguished from a flat surface;

Fig. 8 is a partial top plan view of another modification showing another manner of interconnecting the strips;

Fig. 9 is a partial top plan view of another modification in which the surface strips and elliptical springs are made from separate stock;

Fig. 10 is a partial view in perspective of a preferred form of elliptical spring in which the upper half thereof is cut or stamped from the strip stock; and

Fig. 11 is a view of a blank from which elliptical springs may be formed integral with the strips.

In the following description and in the claims, various details will be identified by specific names for convenience, but they are intended to be as generic in their application as the art will permit. Like reference characters denote like parts in the several figures of the drawings.

For purposes of illustration a preferred embodiment of the invention will be described in connection with a spring bottom for a bed, commonly known as a bed spring.

Referring now to the structure of the bed spring disclosed in the drawings (see Figs. 1-6) the lower frame comprises side rails 10, 11 and

end rails 12, 13. These may be made from suitable angle or channel steel stock and joined as by welding or riveting to form corners. The side rails 10 and 11 are connected by cross members 14 which may be of angle or channel steel stock

suitably fixed to the side rails, as by welding or riveting. These cross members are arranged in spaced relation and form bottom supports for the elliptical springs (described hereinafter) and also add strength and rigidity to the bottom frame.

The upper frame comprises side rails 15, 16 and end rails 17, 18 connected, as by welding, to form corners 19, 20, 21 and 22. This upper frame also may be formed of channel or angle steel stock.

The cross members 14 provide supports for the elliptical springs designated generally by reference character 23, which are preferably arranged in spaced staggered relation, as may be observed more clearly in Fig. 3.

A typical elliptical spring comprises an upper half and a lower half which may be made separately from suitable flat steel stock and then fixed to the surface strips. Or the ellipticals may be made integral with the strips. That is to say, strip steel stock of desired width and length may be stamped out to form an integral blank such as disclosed in Fig. 11.

The blank comprises parallel flat strands 24 and 25 (see Fig. 11) and integrally connected therewith are cross strips 26. Extending from each cross strip 26 are leaf portions 27 and 28 terminating in slightly wider portions 29 and 30 forming heads of the half elliptical spring designated generally by reference character 31 (see Fig. 10). By bending the leaf portions 27 and 28 and flattening out the wider portions 29 and 30, as shown in Fig. 10, the strip so formed provides a plurality of half elliptical leaf springs integral with the strip designated generally by reference character 32.

The lower half of the elliptical (designated generally by reference character 33) may be made from separate sheet stock and formed to complement the upper half elliptical 31. The lower half elliptical comprises a cross piece 34 from which extend leaf members 35 and 36 terminating in head pieces 37 and 38. Cross pieces 26 provided with apertures 39 and 40 to accommodate rivets for attaching cross connecting strips 41 or yielding connecting means such as the helical springs 42 (see Fig. 3). The cross piece 34 forming a supporting base of the lower half elliptical (see Fig. 10) is provided with apertures 44 and 45 for fixing it, as by hollow rivets, to the cross members 14 of the lower frame. When the upper half elliptical 31 is placed in position with its complementary lower half 33, the head portions 29 and 37 register with each other and head portions 30 and 38 register with each other. The heads are connected by helical springs 46, the hook ends of which pass through registering apertures 47.

Having described a typical elliptical spring of the invention, it will be observed that the ends of the strip are anchored to the end rails 17 and 18 by yielding means such as helical springs 42 (see Fig. 1). The surface strips 32 are arranged in parallel relation extending longitudinally and the strips nearest the side rails may be anchored thereto, as by strips 50 and hollow rivets 51 (Figs. 1 and 6) or by helical springs 42 as shown in Figs. 8 and 9.

Preferably, the strips forming the upper supporting surface of the bed spring are arranged as shown in Fig. 1 (see also Fig. 3) in groups of three, save for the strips next adjacent the side rails. The three strips making up what might be termed a section, are connected at the cross pieces 26 of the ellipticals by means of cross connecting strips 41 which may be of thin metal and of a length corresponding to the combined width of the three strips arranged in spaced relation (see a, b and c Fig. 3). These cross connecting strips 41 may be fixed to the longitudinal strips 32 by

any suitable means, as by welding or by hollow rivets 51. The sections thus formed may then be connected by helical springs 42.

When the parts heretofore mentioned are set up and interconnected as shown and described it will be observed that the upper and lower frames are maintained in substantially fixed parallel spaced relation. There will be practically no lateral play between the upper and lower frames relative to each other. To prevent longitudinal play, a stabilizer is provided. This may comprise a metal strip 60 (see Figs. 1, 4 and 5), one end 61 of which may be pivotally connected as by rivets 65 to a corner of the upper frame, the other end 62 of which is connected to a yielding resilient means such as a helical spring 63 which in turn may be anchored to a lug 64 fixed to the side rail about midway of the side rail of the lower frame. Four such stabilizers are desirable, one for each corner. By the provision of these stabilizers undesirable longitudinal play of the upper and lower frames relative to each other is eliminated.

A bed spring or spring bottom thus constructed meets the requirements necessary to its intended purpose. The arrangement of the elliptical springs may be such as to produce the comfortable feeling of a so-called soft spring, yet there is sufficient resiliency to afford ample rigidity with the sensation of firm support.

When a load is placed upon the resilient supporting surface formed by the surface supporting strips, the elliptical springs tend to flatten out. Simultaneously, there is sufficient yield or "give" when the helicals 42 are stressed to permit the flexible metal surface supporting strips 32 to assume the general shape or contour of the load. Meanwhile, the helicals 46 exert a force tending to oppose the flattening out of the elliptical springs heads and the flattening out of the ellipticals. The respective hook ends of helicals 46 are anchored through the registering apertures 47 of the registered heads of the half ellipticals, thus the whole elliptical is kept in proper alignment when it is stressed, yet with sufficient "give" on the various single members which are distended to produce the desired combined resiliency effect. When the load is removed the various stressed members quickly resume their original positions without obnoxious squeak or undesirable noise.

In the modification illustrated in Fig. 8, the surface forming strips, instead of being arranged in groups of three parallel strips to form three strip sections as hereinbefore described, may be connected in such manner that helical springs 42 connect each strip 32 to its adjacent strip. The side strips 32a may be connected to the side rails 15 and 16 of the upper frame by helicals 42. The ends of the strips may in like fashion be connected by helicals 42 to the end rails 17 and 18 of the upper frame.

As illustrated in Fig. 9, flat strips 132 may be used in place of the strips 32 which have been stamped out or stenciled to form integral half ellipticals. In such cases two half ellipticals, such as the lower half ellipticals 33 (as shown in Fig. 10) may be connected and the elliptical thus formed, designated generally by reference character 123, may be secured to the flat strip 132 as by hollow rivets 51. The strips may then be connected to the frames and to each other and to the lower frame supporting members in such manner or manners as hereinbefore described.

If it is desired to make a spring bottom which requires a resilient supporting surface other than a flat or level resilient supporting surface, such, for example, as a resilient spring bottom support for an automobile seat, or other upholstered part, this may be accomplished within the contemplation of the invention.

Referring to the construction illustrated in Fig. 7, elliptical springs 123a, b, c, d, e, and f of different sizes and heights, constructed as hereinbefore described, may be arranged as desired and fixed to the supporting members 14a of the lower frame. The upper resilient surface of the spring bottom may be formed by longitudinally extending strips 132b, c, d, e and f connected by cross connecting strips 150 and 141. In like manner as heretofore described, the ellipticals of different heights may be connected to the strips.

As shown in the illustrative drawings (Fig. 7) the surface strip 132b is connected to the side rail 16a by connecting strip 150 and to its adjacent surface strip 132c by helicals 42. Strips 132c, d, e and f are interconnected to form a section of four parallel surface strips by cross connecting strips 141 shaped to conform to the surface configuration presented by the elliptical springs 123c, d, e and f.

Thus it will be observed that a resilient supporting surface having the characteristics hereinbefore described may be produced according to the invention which may be of various desirable conformations as distinguished from a flat resilient supporting surface. Such surface configurations are admirably suited to vehicle seats and odd shaped objects and parts where upholstering is applied.

From the foregoing description it will be apparent that various modifications within the contemplation of the invention will suggest themselves to those skilled in the art. And while certain novel features of the invention have been disclosed herein and are pointed out in the annexed claims, it will be understood that various omissions and changes may be made by those skilled in the art without departing from the spirit of the invention.

What is claimed is:

1. A spring bottom which comprises a lower and an upper frame, a plurality of elliptical springs mounted on said lower frame, means including strips mounted on said springs forming a resilient load supporting surface, said elliptical springs including an upper half elliptical having outwardly directed, oppositely disposed apertured head portions and a lower half elliptical having corresponding outwardly directed, oppositely disposed apertured head portions, the apertures in the head portions of the upper and lower half ellipticals being in registered alignment, helical springs having their ends hooked through said registered aligned apertures to maintain said head portions in aligned registry and exerting a force tending to oppose distention of said oppositely disposed heads when a load is placed on said surface tending to distend said oppositely disposed heads.

2. A spring bottom which comprises a lower and an upper frame, a plurality of elliptical springs mounted on one of said frames, means including strips mounted on said springs forming a resilient load supporting surface, said springs including an upper semi-elliptical having outwardly directed, oppositely disposed apertured head portions and a lower semi-elliptical having

corresponding outwardly directed, oppositely disposed apertured head portions, apertures in said upper and lower head portions in aligned registry, and yieldable resilient means extending through the aligned apertures to maintain said upper and lower head portions in registered face to face engagement and exerting a force opposing distention of the oppositely disposed head portions when a load is placed on said surface causing a flattening of said ellipticals.

3. A spring bottom comprising an upper frame and a lower frame, cross members for strengthening said lower frame and affording supports for springs, elliptical springs mounted on said members, said elliptical springs having an upper half having outwardly directed apertured heads and a lower half having corresponding outwardly directed apertured heads, means connecting the apertured heads of said upper half ellipticals in face to face registered contact with the corresponding heads of said lower half elliptical, said means comprising helical springs hooked through the apertures of said heads, flexible strips mounted on said elliptical springs, said strips being arranged in rows and interconnected with each other and resiliently connected to said upper frame and forming a resilient supporting surface, and yieldable resilient means connected to said upper and lower frames acting as a stabilizer to prevent play between said upper and lower frames relative to each other.

4. A spring bottom which comprises a lower frame, a plurality of supporting members connecting with said lower frame, a plurality of elliptical springs having bases fixed to said supporting members, each of said elliptical springs comprising an upper and a lower semi-elliptical member each having outwardly directed corresponding head portions, the outwardly directed head portions of said upper semi-elliptical members connected in face to face registered contact with the corresponding outwardly directed head portions of said lower semi-elliptical members forming in each elliptical spring two pairs of oppositely disposed face to face head portions, resilient means connecting each pair of face to face head portions with its oppositely disposed pair of face to face head portions and exerting a force tending to oppose distention of said semi-elliptical members when a force is applied tending to flatten said elliptical springs, means including surface supporting members fixed to the upper semi-elliptical members of said elliptical springs forming a resilient load supporting surface, an upper frame, and means connecting the resilient load supporting surface to said upper frame.

5. A spring bottom which comprises a lower frame, a plurality of supporting members connecting with said lower frame, a plurality of elliptical springs having bases fixed to said supporting members, each of said elliptical springs comprising an upper and a lower semi-elliptical member each having at its oppositely disposed ends an outwardly directed head portion, the corresponding head portions being in face to face contact and having apertures therein, the apertures of the head portions of the upper semi-elliptical members registering with the apertures of the lower semi-elliptical members, helical springs having hooked ends extending through the registered apertures linking said face to face head portions together and exerting a force tending to oppose distention of said semi-elliptical members when a force is applied tending to flatten said elliptical springs, means including sur-

face supporting members fixed to the upper halves of said elliptical springs forming a resilient load supporting surface, an upper frame, means connecting the resilient load supporting surface to said upper frame, and stabilizers connected to said upper and lower frames to inhibit play between said upper frame and lower frames relative to each other when a lateral force is exerted on said load supporting surface.

6. In a spring bottom having a resilient load supporting surface, an elliptical spring which comprises an upper half section including a cross piece, leaf portions extending from said cross piece and terminating in wider portions forming oppositely disposed heads, apertures in said heads, a lower half section complementing said upper half and including a cross piece, leaf portions extending from said last mentioned cross piece and terminating in wider portions forming oppositely disposed heads in registry with said first mentioned heads, apertures in said second mentioned heads aligned with the apertures of said first mentioned heads and yieldable resilient means connecting said oppositely disposed heads, said resilient means comprising helical springs having hooked ends passing through said aligned apertures and serving to maintain said two half sections in alignment and exerting a force tending to oppose distention of said oppositely disposed heads.

7. A spring bottom comprising an upper frame and a lower frame, cross members for strengthening said lower frame and affording supports for springs, elliptical springs of different and graduated heights mounted on said members, each of said elliptical springs comprising an upper half section having outwardly directed oppositely disposed head portions, a complementary lower half section having outwardly directed oppositely disposed head portions in face to face contact and linked to the corresponding head portions of said upper half section, helical springs connecting the oppositely disposed linked contacting head portions and maintaining them under tension, flexible strips mounted on said elliptical springs of different and graduated heights, said strips being mounted in orderly graduated arrangement as distinguished from haphazard arrangement, said strips being arranged in rows and interconnected with each other, and to said upper frame and forming a resilient supporting surface of generally rounded, as distinguished from flat, conformation.

8. A spring bottom comprising an upper frame and a lower frame, cross members for strengthening said lower frame and affording supports for springs, elliptical springs of different and graduated heights mounted on said members, each of said elliptical springs comprising an upper half section having outwardly directed oppositely disposed head portions, a complementary lower half section having outwardly directed oppositely disposed head portions in face to face contact and linked to the corresponding head portions of said upper half section, helical springs connecting the oppositely disposed linked contacting head portions and maintaining them under tension, said elliptical springs being mounted on said cross members in orderly graduated arrangement as distinguished from haphazard arrangement, flexible strips mounted on said elliptical springs, said strips being arranged in rows and interconnected with each other, and to said upper frame and forming an uneven and generally rounded resilient supporting surface, as distinguished

from a flat surface, and yieldable resilient means connected to said upper and lower frames acting as a stabilizer to prevent play between said upper and lower frames relative to each other.

9. A spring bottom which comprises a lower frame having side and end rails, a plurality of supporting members arranged in parallel relation connecting with said side rails, a plurality of elliptical springs of graduated heights having bases fixed to said supporting members, each of said elliptical springs comprising an upper half section having outwardly directed oppositely disposed head portions, apertures in said head portions, a lower half section complementary to said upper half section having corresponding outwardly directed oppositely disposed head portions in registry and face to face contact with the head portions of said upper half section, apertures in the head portions of said lower half section in alignment with the apertures of the head portions of said upper half section, helical springs having hooked ends extending through aligned apertures and connecting said oppositely disposed heads to maintain said upper and lower half sections in alignment and exerting a force tending to oppose distention of said heads when a force is applied tending to flatten said elliptical springs, said elliptical springs being arranged in orderly and graduated fashion as distinguished from haphazard arrangement, and surface supporting strips fixed to the upper half of said elliptical springs of different heights whereby to form a resilient load supporting surface of raised and graduated, as distinguished from flat, conformation.

10. A spring bottom which comprises a lower frame having side and end rails, a plurality of supporting members arranged in spaced parallel relation connecting with said side rails, a plurality of elliptical springs spaced in parallel staggered relation having bases fixed to said supporting members, each of said elliptical springs comprising an upper half section having outwardly directed oppositely disposed apertured heads, a complementary lower half section having outwardly directed oppositely disposed apertured heads in face to face contact with the heads of said upper half section and linked thereto to maintain said contacting heads in registry, helical springs having their ends extending through the apertures to link said corresponding half sections together and connecting said oppositely disposed contacting heads to maintain said upper and lower halves in alignment and exerting a force tending to oppose distention of said heads when a force is applied tending to flatten said elliptical springs, surface supporting strips fixed to the upper half of said elliptical springs and arranged in parallel spaced relation, an upper frame having side and end rails, yielding resilient means connecting the ends of said strips to said end rails, means connecting the surface strips next adjacent to the side rails of the upper frame to said side rails, and means connecting adjacent surface supporting strips to each other whereby to form a flexible resilient load supporting surface.

11. A spring bottom which comprises a lower frame having side and end rails, a plurality of supporting members arranged in spaced parallel relation connecting with said side rails, a plurality of elliptical springs spaced in parallel staggered relation having bases fixed to said supporting members, each of said elliptical springs comprising an upper half section having outwardly

directed oppositely disposed apertured heads, a complementary lower half section having outwardly directed oppositely disposed apertured heads in face to face contact with the heads of said upper half section and linked thereto to maintain said contacting heads in registry, helical springs having their ends extending through the apertured heads and connecting said oppositely disposed contacting heads to maintain said upper and lower halves in alignment and exerting a force tending to oppose distention of said heads when a force is applied tending to flatten said elliptical springs, surface supporting strips fixed to the upper half of said elliptical springs and

arranged in parallel spaced relation, an upper frame having side and end rails, yielding resilient means connecting the ends of said strips to said end rails, means connecting the surface strips next adjacent to the side rails of the upper frame to said side rails, means connecting adjacent surface supporting strips to each other whereby to form a flexible resilient load supporting surface, and stabilizers connected to said upper and lower frames to inhibit play between said upper frame and lower frame relative to each other when a lateral force is exerted on said load supporting surface.

JAMES PILIERO.
